UNITED STATES PATENT OFFICE.

HERMAN W. LAMPMAN, OF LAGRANGE, INDIANA.

LIFTING-JACK.

1,064,076.

Specification of Letters Patent. Patented June 10, 1913.

Application filed February 28, 1912. Serial No. 680,541.

To all whom it may concern:

Be it known that I, HERMAN W. LAMPMAN, a citizen of the United States, residing at Lagrange, in the county of Lagrange and State of Indiana, have invented a new and useful Lifting-Jack, of which the following is a specification.

This invention relates to lifting jacks and is particularly designed for use in elevating 10 motor vehicles and the like.

One of the objects of the invention is to provide a lifting jack which is simple and durable in construction, all parts thereof being made of stock of standard or commercial 15 forms, the said jack being compact in construction and easy to operate.

A further object is to provide a lifting jack which can be adjusted so as to support a vehicle at a desired distance from the 20 ground.

With the foregoing and other objects in view which will appear as the description proceeds, the invention resides in the combination and arrangement of parts and in 25 the details of construction hereinafter described and claimed, it being understood that changes in the precise embodiment of the invention herein disclosed can be made within the scope of what is claimed, without 30 departing from the spirit of the invention.

In the accompanying drawings the preferred form of the invention has been shown.

In said drawings:—Figure 1 is a perspective view of the jack, one of the positions 35 of the movable parts being indicated by dotted lines. Fig. 2 is a side elevation of the structure. Fig. 3 is an enlarged front elevation of upper portion of the jack, the head being elevated. Fig. 4 is a detail view of the 40 slide. Fig. 5 is an enlarged section on line A—B Fig. 3. Fig. 6 is an enlarged section on line C—D Fig. 1.

Referring to the figures by characters of reference 1 designates a metal base preferably formed in a single plate having its central portion upstruck so as to constitute the bearing for the base of the standard of the jack. This standard is formed of a single length of channel steel or the like bent to 50 form a straight base 2 the ends of which merge into upwardly converging members 3 terminating in upwardly extending parallel arms 4. The channel is formed in the inner faces of the arms 4 and forms guide ways 55 5 for the reception of a slide made up of a single length of steel or the like such as

shown at 6, the said strip being folded so as to form parallel longitudinally extending portions fitting snugly between the flanges on the arms 4, as shown in Fig. 5. The 60 crown portion of the slide formed where the parallel portions thereof merge, forms an enlargement 7 to which is secured a curved plate 8 forming the head of the jack. This head is preferably connected to said 65 enlargement by a single rivet 9 and it will be apparent, therefore, that the head can be rotated relative to the enlargement. The upper or concave face of the plate is preferably provided with a cushion 10 of leather or 70 the like. A longitudinal series of openings 11 is formed in each of the parallel members of the slide 6, as shown particularly in Fig. 4. The base 2 of the standard is attached to the base 1 by means of rivets 12 or the like 75 so that the standard is thus held fixed relative to the base 1.

A bolt 13 is extended transversely through the base portion 2 of the standard and upwardly extending links 15 are pivotally mounted on this bolt and extend along opposite sides of the standard. The upper end portions of the links are pivotally connected, as by means of studs 16, to the sides of a lever 17, said lever straddling the standard 80 and the slide and being pivotally connected to the slide close to the enlargement 7. The free end portion of the lever is enlarged to form a loop 19 and said looped portion is preferably offset, as indicated particularly 85 in Fig. 2, so that, when the slide 6 and the head 8 are elevated, the loop 19 is free to straddle one of the upwardly converging portions 3 of the standard while the remaining portions of the lever move into position between the links 15 and one of the arms 4. This is illustrated in Fig. 2. The lever 17 is preferably connected to the slide 6 by means of a pin 20 insertible through 90 any of the openings 11 in the slide 6 and said pin is prevented from being withdrawn from the openings and the lever by a cotter pin 21 or the like engaging one end thereof.

It will be apparent that, by offsetting the looped portion 19 of the lever, said lever can 95 be swung inwardly a sufficient distance toward the standard to bring the pivots 16 past the vertical line passing through the pin 20, and as shown in Fig. 2, when the parts are thus positioned the jack will support any weight which may be applied to the head 8 without danger of the lever 17

swinging upwardly and permitting the slide 6 to move downwardly. As the pivots 16 are very close to the pin 20, it will be seen that considerable leverage can be had by 5 means of this jack.

In using the device, the jack is placed under the part to be lifted and pin 20 is removed. Lever 17 is then swung about 45 degrees above the horizontal after which the 10 slide 6 is moved upwardly until the cushion 10 comes into contact with the part to be lifted. Pin 20 is then inserted through lever 17 and through the opening 11 in alinement with the pin. After the pin has been secured by means of the cotter 21, the looped end 19 of the lever is pushed downwardly. 15 Slide 6 will thus be forced upwardly and the head 8 will cause the part in the path thereof to be elevated. In moving the lever 20 17 downwardly to its greatest extent, the pivots 16 are moved under the pin 20 and past the dead center so that the jack becomes self-locking and will support the weight to which it is subjected, without the use of any 25 special locking means. To lower the head 8 and the parts supported thereby, it is merely necessary to swing the looped end 19 of the lever upwardly so as to bring the pivots 16 from under the pin 20 whereupon the 30 weight of the object being supported will cause the slide 6 to move downwardly and the lever 17 to swing upwardly.

It will be seen that the jack can be actuated by pressing lever 17 downwardly with 35 the foot and by pushing the lever upwardly in the same manner. As the head 8 is swiveled on the slide 6 and is arranged directly over it at all times, it will be seen that the jack can be placed so as to cause the lever 40 to extend in any desired direction from under the part to be lifted so as thus to suit the convenience of the operator.

The arms 4 are prevented from spreading apart at their upper ends, by a tie 22 which 45 extends through said arms adjacent their upper ends and also extends between the side members of the slide 6. This tie can be in the form of a rivet, bolt or the like.

If desired, the base 1 may be formed at 50 one end, with an angular wing or extension 23 inclined so as to fit snugly on one of the upwardly converging portions 3, said extension being riveted or otherwise fastened to said portion. Furthermore, and as shown in 55 Fig. 5, the members of the slide 6 are preferably slightly bowed transversely so as to fit snugly within the channelled members 4 and, furthermore to reinforce the slide 6.

Spacing washers 24 are preferably inter- 60 posed between the lower ends of the links 15 and the base portion 2, these washers being mounted on the bolt 18.

The tie 22 is preferably constructed as shown in Fig. 6 wherein it is shown as made 65 up of a spacing plate 25 from which studs

26 project, these studs being fastened within the members 4.

Instead of providing a single wing or extension 23 on the base 1, two or more extensions may be employed.

It might be stated that the amount of leverage obtained by the use of this jack can be varied by changing the relative positions of the pivot 16 and the pin 20, thus adapting the jack to the load which it is expected to 70 75 lift.

It is to be understood that after the jack has once been adjusted for a certain vehicle it is not necessary to change the adjustment. The quick action of the jack renders it especially desirable for use in supporting vehicles in order to relieve their tires of constant weight while in storage.

What is claimed is:—

1. A jack including a base, a standard 85 thereon formed in a single length of channeled material, said standard having upstanding spaced portions with their channels innermost, a slide formed in a single length of metal folded to form parallel 90 spaced members mounted within the channels in said standard, a tie connecting the channelled members of the standard and extending between the members of the slide, and means for shifting the slide longitudinally 95 relative to the standard.

2. A jack including a base, a channeled strip secured on the base and having upstanding portions forming a standard, the channel being formed in the inner faces of 100 said portions, a tie connecting said portions, a slide mounted within the channels in the upstanding portions and consisting of a single length of metal folded upon itself to form opposed parallel portions, the tie being 105 extended between said parallel portions, and means for shifting the slide longitudinally relative to the standard.

3. A jack including a base, a channeled strip secured on the base and having upstanding portions forming a standard, the channel being formed in the inner faces of 110 said portions, a tie connecting said portions, a slide mounted within the channels in the upstanding portions and consisting of a 115 single length of metal folded upon itself to form opposed parallel portions, the tie being extended between said parallel portions, means for shifting the slide longitudinally relative to the standard, a link pivotally connected to the lower portion of the standard, a lever pivotally connected to the slide, and a pivotal connection between the lever and link.

4. A jack including a base, a channeled 125 strip secured on the base and having upstanding portions forming a standard, the channel being formed in the inner faces of 130 said portions, a tie connecting said portions, a slide mounted within the channels in the

upstanding portions and consisting of a single length of metal folded upon itself to form opposed parallel portions, the tie being extended between said parallel portions, means for shifting the slide longitudinally relative to the standard, a link pivotally connected to the lower portion of the standard, a lever pivotally connected to the slide, and a pivotal connection between 10 the lever and link, said connection being shiftable past the lever and slide to lock the slide in elevated position.

5. The combination with a base, of a standard formed in a single length of channeled material and including upwardly extending portions having the channel in the inner faces thereof and forming a guide, a slide within said guide and formed in a single length of metal folded on itself, a lever 20 straddling the slide and standard and pivotally and adjustably connected to the slide, and links connecting said lever and the base portion of the standard, the points of connection between the links and the lever being 25 shiftable past the dead center to lock the slide in elevated position.

6. A jack including a base, a longitudinally channeled strip secured on the base and having upwardly converging portions 30 merging into upwardly extending arms, the channel being formed in the inner faces of the arms, a tie connecting the arms, a slide interposed between and guided by the arms, said slide consisting of a single length of 35 metal folded to form spaced parallel portions, there being an enlargement at the upper ends of said portions, a head on the enlargement, links pivotally connected to the lower portion of the standard, a lever

pivotal and adjustably connected to the 40 slide, and pivotal connections between the lever and the links, said last named connections being shiftable past the dead center to lock the slide in elevated position.

7. A jack including a base, a standard 45 secured on the base and formed in a single length of channeled material, said standard having upstanding opposed portions with channels in their inner faces, a wing upon the base and lapping and secured to one of 50 said upstanding portions, spacing means for tying said upstanding portions together, a slide mounted between and guided by the flanges on said upstanding portions, and means for shifting the slide within the 55 standard.

8. A jack including a base, a standard thereon formed in a single length of channeled material, said standard having upstanding spaced portions with their channels innermost, a slide formed in single length of metal folded to form parallel spaced members mounted within the channels in said standard, said members being bowed transversely, a tie connecting the 60 channeled members of the standard and constituting spacing means, said tie extending between the members of the slide, and means for shifting the slide longitudinally relative to the standard. 65

In testimony that I claim the foregoing as my own, I have hereto affixed my signature in the presence of two witnesses.

HERMAN W. LAMPMAN.
